CHRISTOPHER MOEGLING, OF MILWAUKEE, WISCONSIN.

Letters Patent No. 62,966, dated March 19, 1867.

IMPROVEMENT IN GRINDING-MILLS.

The Schedule referred to in these Letters Patent and making part of the same.

TO ALL WHOM IT MAY CONCERN:

Be it known that I, CHRISTOPHER MOEGLING, of Milwaukee, State of Wisconsin, have invented certain new and useful improvements in Attachments to Grain-Mills for cooling, evaporating, and ventilating purposes; and I do hereby declare the following to be a full and exact description of the same, reference being had to the drawing, that accompany and form a part of these specifications, in which—

Figure 1 is a side elevation, with a portion of the curb removed to bring in view the stone and the attachments thereto.

Figure 2, detached parts, the same being shown in fig. 1, arranged upon the stone.

Figure 3, sectional view cut through the centre of the stone.

Letter A, the upper millstone; B, the curb; C, the bed-stone; D D', metal bands encircling the stone A, as shown in fig. 1; E E E, wings or fans attached to the bands D D'; F, hopper from which the grain is fed; g, a tube extending from the cover somewhat into the opening of the stone, (see fig. 1;) h, cover above the upper stone; I, pipe for carrying off the air; J, a cap fitted to the lower end of the pipe I, and gathers the refuse that may fall in the tube L; k, elbow connecting the interior of the curb with the pipe I; m m, flanges on the lower end of the elbow or pipe k; n n, strips fastened to the top or cover of the curb, and bear upon the flanges m m to keep the pipe k in position; O, an opening in the cover h leading to the tube k; P, a slide used to regulate the amount of opening at O; r r, bolts joining the straps D D'; s' s', rivets connecting the wings E E E with the straps or bands D D'.

The object of my invention is not merely to furnish a cooling device, but to provide one that shall afford evaporation and ventilation as well. It is well known by millers that the heat developed by the process of grinding sets free much moisture. The current of air, in ordinary mills, arising from the grinding surfaces brings up much dust which falls upon and renders foul everything in the mill; it is, moreover, very pernicious to the lungs of those employed about the mill.

My invention consists in a device that keeps constantly forcing the air, that lies between the curb and the upper stone, out and through a funnel or tube out of the building; this will, as a matter of course, induce a current down through the feed opening of the stone A and along the grinding surfaces, to keep up the supply of air that is being constantly carried off. The particular parts of my device are as follows:

The bands D and D' may be of wood, metal, leather, rubber, or any suitable material. These quite encircle the stone, and upon them, arranged as the drawings show, are placed a series of strips or wings of sheet metal, which, in width, are sufficient to very nearly fill the space between the stone A and the curb B. They do not extend so low as to the base of the stone A, as may be seen in fig. 1. The bands D and D' may be turned around horizontally on the stone A, the wings E being attached each end by a single loose rivet only. The effect of moving one of the bands would be to cause the wings E to incline to the right or left according to which of the bands was moved, and the direction. The above arrangement provides for gauging the force of the wings E; when they are upright, they will exert their greatest force; when inclined, they will fill less space in a vertical direction, and consequently have less effect on the air when they rotate with the stone. The object of the tube g is to prevent air from passing into the space between the curb and the stone over the stone A.

The operation of my device is this: The stone A, with my attachments, is set in motion, and there is always a rush of air to the periphery thereof, and the pipe that conducts away the air, being over the outer edge of the stone or over the space between the stone and curb, receives this air and conducts it away. This causes the draught of air down through the opening of the stone A, which is always considerable, to be much increased, and a constant current of air is kept up down through the stone A, along the grinding surfaces of the stones, with the grinding grain, and then off through the pipe I, taking away that fine, impalpable dust that is so annoying and destructive, and the dampness that is set free by the grinding process, and thus keeping the mill clean, the stones cool, sweetening the flour, and drying it so that it bolts better, and in damp wheat very materially increasing the quantity and producing a complete ventilation, which latter, in grain mills, is of great importance. The cap J can be taken off as often as may be found necessary, and the refuse that may have gathered there thrown out. Small pipes leading from the different sets of stones to one large educting pipe would be the arrangement where several run of stones are used. The slide P is of great use in regulating the flow of air, a

much freer current being required when the grain is damp than when dry. When it is desired to arrange the wings E otherwise than perpendicular, the top or upper ends of them should recline backwards from the line of rotation, whether it be from left to right or the opposite. That is, if the stones rotate towards the left, the upper ends of the wings should recline, as indicated by their position in fig. 2. If the stone rotates to the right, then the position should be changed to that indicated by the red lines in fig. 2. This declination from a perpendicular should be less or more according as the rotation is slow or rapid. On a four-foot stone, at two hundred revolutions per minute, this declination should be from twelve to fifteen degrees.

I am aware that bands and also wings or fans have been used in the rotating stone of grain mills, also that pipes to conduct the air to the stones and pipes to conduct the heated air away, and I do not claim any one of these broadly; but what I do claim, and desire to secure by Petters Patent, is—

1. The adjustable wings E, in number more or less, when used upon the periphery of the rotating stone of a grain or flouring-mill, for the purposes specified.

2. The pipe g, the cover h, the elbows k, and the educting pipe I, when provided with the cap J, all combined and arranged substantially as set forth, and to operate in connection with the wings E for the purposes specified.

CHRISTOPHER MOEGLING.
